UNITED STATES PATENT OFFICE.

ARTHUR H. PHILLIPS, OF HULBERTON, NEW YORK.

RECEPTACLE FACER.

Application filed May 23, 1924. Serial No. 715,479.

To all whom it may concern:

Be it known that I, ARTHUR H. PHILLIPS, a citizen of the United States, and resident of Hulberton, in the county of Orleans and 5 State of New York, have invented certain new and useful Improvements in Receptacle Facers, of which the following is a specification.

The present invention relates to receptacle facers and an object of the invention 10 is to provide a simple and inexpensive construction which will make it possible to pack fruit or other articles in barrels or other containers in such manner that the top or facing 15 layer will present a good appearance when the container is opened. A further object of the invention is to provide a facer in the form of a receptacle which has a cover adapted to be removably fitted in place on 20 the receptacle and permitting the receptacle to be inverted and fitted in an inverted condition in the container which is to be faced, the cover being released and serving as a cushion for the facing layer in the container.

25 To these and other ends, the invention consists of certain parts and combinations of parts, all of which will be hereinafter described: the novel features being pointed out in the appended claims.

30 In the drawings:

Fig. 1 is a plan view of the receptacle;

Fig. 2 is a bottom view of the receptacle;

Fig. 3 is a sectional view through the receptacle showing the cover in position there- 35 on; and

Fig. 4 is a sectional view showing the receptacle in the container with the cover released.

Referring more particularly to the illus- 40 trated embodiment of the invention, 1 indicates the facing receptacle which has a flaring wall 2, formed of resilient material, the diameter of this wall being slightly greater than the diameter of the opening in the barrel 45 head so that in inserting the receptacle sidewise in the barrel, the edge of the receptacle is slightly compressed in order that, when the receptacle is in position in the barrel, as shown in Fig. 4, the perimeter of 50 the flaring wall will rest upon the barrel staves. The advantage of this is that the fruit or articles may be packed close together in the receptacle and when deposited upon the bottom of the barrel will be compactly arranged upon the head.

With the end in view of permitting the

inversion of the facing receptacle after the fruit or other articles have been placed therein, a cover member 3 is employed, which preferably is in the form of a corrugated 60 paper disk. This disk in addition to acting as a cover for the facing receptacle will act also as a cushion for the fruit in the barrel, the cover member remaining in the barrel or receptacle or container 4 after the facing 65 receptacle 1 is withdrawn.

A means is employed for retaining the cover member in cooperative relation with the facing receptacle when the latter is inverted or is being fitted in the barrel or container 4. This means, in this instance, comprises a plurality of movable devices 5 in the form of flexible cords which pass through tubes 6 on the flaring side walls of the facing receptacle and through the 75 bottom wall 7 of such facing receptacle. A helical spring 8 may connect with one end of each of the movable devices 5 and also with the bottom wall of the receptacle tending normally to hold said movable device 5 80 away from normal position.

With the end in view of holding the movable devices in operative positions, a holding means is employed in the form of a plunger 9 operating through a tube 10 in the center 85 of the facing receptacle and through the bottom wall of such receptacle, the tube being preferably covered by a rubber tube 11 acting as a cushion to prevent the bruising of the fruit. The end of this plunger 9 ex- 90 tends through the tube and is adapted to be engaged by loops 12 on the ends of the retaining cords or devices 5. The cover 3 has a central opening through which the end of the retaining plunger 9 extends in 95 order to be engaged by the loops 12. It is apparent that upon the pulling of the plunger 9 inwardly, the loops 12 will be stripped from the plunger and the cords 5 will move to normal positions under the 100 actions of the springs 8. In order that the plunger 9 may be manipulated from the under side of the facing receptacle, a grip 13 may be provided on the plunger 9, this grip moving the plunger against the action 105 of a spring 14 which surrounds the plunger on the underside of the receptacle and seats against a bar 15 in which the plunger is also guided. The bar 15 connects two U shaped supports 16 which have the dual function 110 of supporting the receptacle, during the filling, upon any suitable surface or for sup-

porting the receptacle, during the facing operation, through the hands of the user of the device.

From the foregoing it will be seen that there has been provided a facing receptacle which has a cover held in position thereon to permit the facing receptacle to be inverted, while holding the articles, the cover being releasable from the facing receptacle when the latter is inverted within a container, so that the cover may remain in the container and act as a cushion for the articles in the container. The cover is held in position by means movably mounted on the facing receptacle and movable away from holding position by springs, provision being made whereby the holding devices may be secured in holding positions and released to the action of the springs from the underside of the receptacle, so that the cover may be released after the receptacle has been inverted within a container.

What I claim as my invention and desire to secure by Letters Patent is:

- 25 1. The combination with a facing receptacle having a bottom wall and a surrounding side wall, of a cover for said facing receptacle formed with material adapted to support articles in the facing receptacle when the latter is inverted, and means for holding said cover in place, said means being mounted on the facing receptacle and being movable thereon to free the receptacle when the facing receptacle is placed in an inverted position within the container so that the cover may remain in the container when the facing receptacle is withdrawn.
- 30 2. The combination with a facing receptacle and a cover for said receptacle, of devices movably mounted on the facing receptacle and adapted to hold the cover in position, springs normally tending to move said devices out of holding positions, and releasable means for holding said devices in holding positions.
- 35 3. The combination with a facing receptacle having a bottom wall and a resilient flaring side wall, of a cover for said receptacle, means for holding the cover in position on the receptacle, and means for controlling said holding means from the bottom of the receptacle.

4. The combination with a facing receptacle, of a cover for the same, holding devices for said cover, springs acting on said holding means to move them away from holding positions, and means for holding said devices in holding positions, said last mentioned means having a portion on the underside of the facing receptacle through which it may be controlled. 55

5. The combination with a facing receptacle, of a cover for said receptacle, devices for holding said cover on the receptacle, springs for moving the said devices away from holding positions, and a plunger controlling said holding devices and having a portion on the underside of the receptacle through which said plunger may be controlled. 65

6. The combination with a facing receptacle, of a cover for said receptacle, flexible holding devices, each having a loop at one end, springs, each connected to the other end of one of the flexible holding devices, and a plunger passing through the loops of the holding devices to hold them in holding positions, said plunger being movable to free the flexible holding devices from the action of the springs in order to release the cover. 70 75

7. The combination with a facing receptacle and a cover for the receptacle, of flexible holding devices, springs for moving said flexible holding devices to free the cover, and releasable means engaging said flexible holding devices to hold them in holding positions. 80 85

8. The combination with a facing receptacle having a bottom wall, of a cover for said receptacle, means for holding the cover in position on the receptacle, and two U shaped supports secured to the underside of the receptacle and formed to hold the receptacle against tilting when its bottom wall is lowermost. 90 95

9. The combination with a facing receptacle having a bottom wall and a flaring side wall, of a cover for the receptacle, and means for holding the cover in position on the receptacle, said means being releasable while the facing receptacle is in an inverted position. 100

ARTHUR H. PHILLIPS.
